INVENTOR
JOHN T. DAVIS
BY F. M. Wright, ATTY.

UNITED STATES PATENT OFFICE.

JOHN T. DAVIS, OF ALAMEDA, CALIFORNIA, ASSIGNOR TO JOHN BURMEISTER, OF SAN FRANCISCO, CALIFORNIA.

COMBINED STEAM-GENERATOR AND OIL-VAPORIZER.

1,372,651.

Specification of Letters Patent. Patented Mar. 22, 1921.

Application filed March 5, 1918, Serial No. 220,474. Renewed August 16, 1920. Serial No. 403,823.

To all whom it may concern:

Be it known that I, JOHN T. DAVIS, a citizen of the United States, residing at Alameda, in the county of Alameda and 5 State of California, have invented new and useful Improvements in Combined Steam-Generators and Oil-Vaporizers, of which the following is a specification.

The object of the present invention is to 10 provide an apparatus for simultaneously generating steam, superheating steam and distilling oil by means of the heat of steam thus generated.

In the accompanying drawing, Figure 1 15 is a cross sectional view of my improved apparatus; Fig. 2 is a longitudinal sectional view on the line 2—2 of Fig. 1.

Referring to the drawing, 1 indicates the 20 wall of a furnace having a burner 2 and a flue 3. A water pipe 4 enters the front wall of said furnace and extends, first, horizontally, and then downwardly therein, and then communicates with the two branch pipes 6. The apparatus is exactly sym- 25 metrical on both sides of a central vertical longitudinal plane, and therefore the description of either side will apply equally to both. Each branch pipe communicates with one end of an annular water, or steam, 30 chamber 7 formed by means of two coaxial cylinders 8, 9, the space between said cylinders being closed at the ends, as shown at 11. From the other end of said chamber 7 a tube 12 leads to one end of an annular 35 chamber 13 formed in a similar manner between two coaxial cylinders 14, 16. From the other end of said chamber 13 leads a tube 17, the other end of which communicates with one end of an annular chamber 18 40 formed in a similar manner between two coaxial cylinders 19, 21. From the other end of said chamber 18, a tube 22 leads and communicates with one end of a chamber 23 formed in a similar manner between two 45 coaxial cylinders 24, 26.

It will have been understood from the above that said annular chambers and cylinders are arranged in pairs, one of each pair in each side of the furnace. From the 50 other end of said annular chambers 26 lead tubes 27 which communicate with a central steam chamber or drum 28 closed at its ends. From the opposite ends of said drum lead downwardly pipes 29, which communicate 55 with the opposite ends of a vaporizer cylin-

der 31. Extending completely across said cylinder at or near its opposite ends are heads 32, and through said leads extend the open ends of small tubes 33.

Oil is supplied by an oil pipe 34 con- 60 trolled by a valve 35, which pipe extends through a hole in the front wall of said furnace and discharges into a chamber 36 between the head 32 in the cylinder 31 and a cap 37 screwed upon the end of said cylinder 31 and completely filling said hole. From said chamber the oil flows into the interior of the small tubes 33, and discharges at the rear end of the tubes into a vapor chamber 38 formed by a cylindrical wall 39 70 screwed on the rear end of said cylinder 31 and filling a hole 41 in the rear wall of the furnace. From the bottom of said chamber 38 leads an oil pipe 42 which passes through the rear wall of the furnace, and the rear 75 side of said chamber 38 communicates with a conduit 43 for conducting away the vapor generated from the oil. A baffle plate 44 is supported by rods 46 from the back wall of the chamber 38 and is located immedi- 80 ately opposite to the rear ends of the small tubes 33.

The following is the mode of operation of the apparatus:

The water, and the steam generated there- 85 from, are very highly heated in the annular chambers 7, 13, 18, 23, by the flames passing around the outer cylinders 8, 14, 19, 24, and through the inner cylinders 9, 16, 21, 26, so that the steam in the uppermost annular 90 chamber 23 is highly superheated. This steam is conducted to the central steam drum 28 where it is again heated still further by the passage of the flames around said drum, so that steam leaving said drum and enter- 95 ing the cylinder 31 is very highly superheated. The heat of the superheated steam is communicated through the walls of the tubes 33 to the oil in said tubes, so that before the oil can flow to the rear ends of 100 said tubes, it is for the most part vaporized. The oil and vapors are projected from said tubes with considerable velocity owing to the expansion which takes place in said tubes in the conversion of the oil into vapor. 105 When the oil and vapor strike the baffle plate 44, that part thereof which is sufficiently heated to retain its vaporous condition, passes around the baffle plate 44 to the conduit 43 which conduit leads to a con- 110

- denser, which is not here shown, as any suitable form of condenser can be used. The part which does not retain its vaporous form, together with the oil projected from the 5. tubes 33, drops to the bottom of the chamber 38 and flows outward by the pipe 42. Any steam condensed in the cylinder 31 escapes by a "bleeder" 54 in the bottom of said cylinder.
- 10 I thus provide means in the same furnace for generating steam, for superheating the steam so generated, and for utilizing steam to vaporize oil, and at the same time conserve and re-heat the steam which has been 15 so utilized to vaporize oil.

I claim:

1. The combination, with a furnace, of a vaporizing cylinder having heads at its ends, a plurality of tubes having open ends 20 extending through said heads, means for forming an oil chamber with one end of the cylinder and the adjacent head, means for feeding oil to said chamber, a vapor chamber communicating with the tubes through 25 the other end of the vaporizing cylinder, a baffle plate therein opposite said tube ends, vapor and oil conduits leading from said vapor chamber, a vertical series of pairs of coaxial tubes in said furnace, the chamber 30 between the tubes of each pair being closed at the ends, the inner tubes being open at the ends, means for supplying water to the lowermost of said chambers, means for conducting aqueous fluid from said lowermost chamber to each of the upper chambers in succession, the tube conducting aqueous fluid to each chamber being at the opposite end to that conducting aqueous fluid from the chamber, a steam drum, means for conducting 35 steam from the uppermost chamber of the series to said steam drum, and communications between the opposite ends of the steam drum and the corresponding ends of the first-named cylinder.
- 40 2. The combination, with a furnace, of a

vaporizing cylinder having heads at its ends, a plurality of tubes having open ends extending through said heads, means for forming an oil chamber with one end of the cylinder and the adjacent head, means for feeding oil to said chamber, a vapor chamber communicating with the tubes through the other end of the vaporizing cylinder, vapor and oil conduits leading from said vapor chamber, a vertical series of pairs of coaxial tubes in said furnace, the chamber between the tubes of each pair being closed at the ends, the inner tubes being open at the ends, means for supplying water to the lowermost of said chambers, means for conducting aqueous fluid from said lowermost chamber to each of the upper chambers in succession, a steam drum, means for conducting steam from the uppermost chamber of the series to said steam drum, and communications between the opposite ends of the steam drum and the corresponding ends of the first-named cylinder.

3. The combination, with a furnace, of a vaporizing cylinder having heads at its ends, a plurality of tubes having open ends extending through said heads, means for forming an oil chamber with one end of the cylinder and the adjacent head, means for feeding oil to said chamber, a vapor chamber communicating with the tubes through the other end of the vaporizing cylinder, vapor and oil conduits leading from said vapor chamber, a vertical series of pairs of coaxial tubes in said furnace, the chamber between the tubes of each pair being closed at its ends, the inner tubes being open at the ends, means for supplying water to the lowermost of said chambers, means for conducting aqueous fluid from said lowermost chamber to each of the upper chambers in succession, and communications between the uppermost chambers of the series and the vaporizing chamber.

JOHN T. DAVIS.
